(57) **CLAIM**

The ornamental design for a light bull bar for vehicles, as shown and described.

DESCRIPTION

FIG. 1 is a front perspective view of the light bull bar for vehicles of the present invention;

FIG. 2 is a front view of the light bull bar for vehicles shown in FIG. 1;

FIG. 3 is a rear view of the light bull bar for vehicles shown in FIG. 1;

FIG. 4 is a side view of the light bull bar for vehicles shown in FIG. 1 with the other side being a mirror image;

FIG. 5 is a top view of the light bull bar for vehicles shown in FIG. 1; and,

FIG. 6 is a bottom view of the light bull bar for vehicles shown in FIG. 1.

The broken lines shown in the drawings are for the purpose of illustrating environmental structure and form no part of the claimed design.
